UNITED STATES PATENT OFFICE.

ALEXANDER W. COPLAND, OF DETROIT, MICHIGAN.

WAFER-COATING MACHINE.

SPECIFICATION forming part of Letters Patent No. 789,655, dated May 9, 1905.

Application filed September 26, 1904. Serial No. 225,966.

To all whom it may concern:

Be it known that I, ALEXANDER W. COPLAND, a citizen of the United States, residing at Detroit, in the county of Wayne and State 5 of Michigan, have invented certain new and useful Improvements in Wafer-Coating Machines, of which the following is a specification, reference being had therein to the accompanying drawings.

10 The invention relates to machines for coating baked goods, and is intended particularly in the particular construction herein shown for coating sheets of baked batter or dough which are afterward intended to be cut up 15 into smaller sizes to make sandwich-wafers.

The invention consists particularly in the construction of a machine for flattening the wafer-sheet and holding it for applying the filling to one sheet and subsequently for pressing a superimposed or upper sheet upon the lining to complete the article preparatory to being cut up.

20 The invention further consists in the construction, arrangement, and combination of 25 parts, as more fully hereinafter described, and particularly pointed out in the claims.

In the drawings, Figure 1 is a vertical central section through my improved machine, showing the drive mechanism in elevation and 30 partly in section. Fig. 2 is a top plan view thereof. Fig. 3 is an elevation looking from the right hand of Fig. 2, partly in section. Fig. 4 is a horizontal section on the line $\alpha\alpha$ of Figs. 1 and 3. Fig. 5 is a vertical section 35 through a modified form of machine.

A is the base of the machine, which has secured to it the hollow standard B, which has a suitable stationary top C.

D is a rotary table having depending from 40 its middle portion the tubular sleeve D', which surrounds the standard B and at its lower end is provided with a gear-wheel E. At four equidistant points on the rotary table D are secured the sheet-plates F of suitable size to 45 receive and support the wafer-sheets which are to be coated and made into sandwich form. This rotary table, with the sheet-plates thereon, is rotated and raised and lowered by the following mechanism: G is a drive-shaft

driven from any suitable power and having 50 thereon the worm meshing with the worm-wheel G' on the transverse shaft G². On the shaft G² is a cam H, on which bears a roller H', supported in the ends of the rock-arms H², which are loosely sleeved on the transverse 55 shaft I. To the rock-arms H² are secured the two arms I', which extend around the side of the standard B and are provided at their ends with rollers a, bearing on the under side of the annular gear E. The cam is so shaped 60 that in each revolution thereof the rock-arms H² and I' will be rocked and the rotary table will be raised and lowered. On the end of the shaft G² is a crank J, having a roller-wrist engaging in a slot b of the lever J', that 65 lever being journaled at c on a stub-shaft on the base of the machine. From the lever J' is a connecting-rod K, which connects to the rock-arm K' on the shaft K² on the opposite side of the machine. This rock-arm carries 70 a pawl d, adapted to engage a notched wheel L on the shaft K² and in the forward movement thereof rotate the same. On the shaft K² is a bevel gear-wheel d', meshing with a bevel-pinion e on the vertical shaft I'. Se- 75 cured to the upper part of the pinion e is a gear-wheel M, which meshes with the gear-wheel E and which is of sufficient length to permit of an up-and-down movement of the gear-wheel E in relation to the gear-wheel M 80 without disengagement therefrom.

Through the connection described at each rotation of the shaft G² the rock-arm K' will be moved forward, and through the gearing described the table and the plates thereon will 85 be rotated a quarter-revolution. It is obvious from the description thus far given that the plates will stop at four equidistant points in each rotation, and for convenience of reference I will number these points, as shown in 90 Fig. 2, as 1, 2, 3, and 4. At the first stopping-point 1 the operator lays a wafer-sheet upon the plate which is in front of it, and it is desirable that the sheet should be clamped tightly upon the plate, and this is effected by 95 the following mechanism: Above the station 1 is a clamping-plate O, secured to the arm O', which is in turn secured to the upper end

of the shaft O^2 , extending centrally above the table C and down into the hollow standard B, where it is supported in suitable guides. Connected to the shaft O^2 is the rod P, which in 5 turn is connected to the outer end of the lever P' , journaled at h in the base of the machine and having a roller i on its end engaging with a cam Q on the shaft G^2 .

At the proper point of time the reduced 10 portion of the cam Q will come opposite the roller i and allow the plate O to lower by gravity upon the wafer-sheet, which is upon the sheet-plate at the position 1. These sheets are more or less wavy or uneven, and this 15 pressing will temporarily flatten them out. In order to hold them flat, I provide clamping means for the edges. These clamping means are of the following construction: k represents four horizontal shafts arranged 20 under each sheet-plate contiguous to the edges thereof and geared together at the corners by bevel-gears, as shown at l . The inner shaft of each set is provided with a rock-arm l' , which is connected by a link m with a bell-crank lever m' , journaled on the table D. The lower end of the bell-crank rests against a pin n . This projects inside the sleeve D'. At the point 1, as shown in Fig. 4, as the table 25 is raised this pin will impinge upon and be pressed out by an inclined lug o on the standard B, which will rock one of the shafts k , and through the gear connection the other shafts k will alike be rocked and withdraw the clamping-arms p , each of which is provided with a clamping-flange p' , overlapping the top of the sheet-plate, as shown in Fig. 1. As the table lowers just before its rotary 30 movement, the pin n will drop off of the lug o , and the torsion-springs s on one of the shafts k will cause the rock-arms p to assume their vertical position, as shown in Fig. 1, and cause the clamping-flanges p' to clamp the edges of the sheet for the succeeding operation. During the time the table is lowering 35 and until these clamping-flanges are in their clamping position the plate O lowers with the table, so as to keep the sheet flat until the clamping is effected.

Before the sheet-plate leaves the position 1 40 and moves to the position 2 it will be lowered, the cam H operating the rock-arms H^2 and I' , causing the roller a to lower, and the weight of the table will lower it. When lowered, it is rotated a quarter-turn by the gears M and 45 E. When it reaches the position 2, it will be raised to its uppermost position, (shown in Fig. 1,) and at this position is a frame R, which is open and surrounds the sheet-plate and which has on its inner edges a thin stencil-plate R' , which is directly above the edges 50 of the sheet clamped upon the sheet-plate. To hold the sheet perfectly flat and take out any bends or curves there may be in it, I pref-

erably stretch across this stencil-frame a series of wires R^2 , as shown in Figs. 1 and 2. 65

S is a hopper containing the compound with which it is desired to coat the sheet. This hopper normally rests with its discharge-opening in the bottom upon the part S' of the stationary top C. This hopper is reciprocated 70 over the sheet-plate and over the stencil-frame by the following mechanism: T represents connecting-rods connected to opposite ends of the hopper and attached to levers T', the latter being secured to the shaft I, which is 75 rocked by a rock-arm U, secured to the end thereof and having a roller-wrist engaging a groove in the cam U' on the end of the shaft G^2 . The hopper being reciprocated back and forth over the sheet clamped on the sheet-plate will upset and lower the material thereon, the thickness being determined by the thickness of the stencil-frame. The table will then again be lowered and rotated a quarter-turn by the mechanism described and the sheet 80 will be brought to the position 3. At this position the coated sheet will have placed upon it by the operator another sheet of like size, there being time for the operator to thus superimpose the sheet while the machine is at 85 rest at its stopping-points. The table is again lowered and the clamped sheet is moved into the position 4. Above this position is a presser-plate V, and as the table with the sandwich-sheet rises the two sheets will be pressed 90 tighter together and flattened between the sheet-plate and the presser-plate V. This presser-plate V is adjustably supported on the arm V' of the top C by means of the bolts q and nuts q' . The table again lowers and is 95 moved a quarter-turn to the original position, where the sandwich-sheet is removed, a new one inserted, and the operation repeated. 100

In Fig. 5 I have shown a machine similar to that shown in the other figures, except that the wafer-sheet is flattened and is held in its flat condition by pneumatic means instead of by mechanical means. In this view I use the same standard B, except that I put a partition T^2 across the upper part and the same rotary table D, except that I form conduits T^3 from the vertical portion thereof beneath the sheet-plates. The sheet-plates in this case I show as simply perforated plates, as illustrated at S^2 . In the standard B, I make apertures S^3 , which connect the interior of the standard with the interior of the sleeve D', and then connect the interior of the standard with any suitable air-exhausting means, so that a vacuum will be produced beneath the 110 sheets on the sheet-plate, and they will be held tightly thereon during the various operations by the atmospheric pressure on top so long as the vacuum is beneath. This enables me to dispense with the presser-plate O and the means for operating it and also the clamp- 115 120 125

ing plates p and the mechanism for operating them. Either the mechanical flattening and clamping or the pneumatic flattening and clamping may be employed, and I believe both are within the spirit of my invention.

The details of the invention may be modified obviously in a number of other ways, and I do not desire to be limited to the specific details herein shown except where such details are made the subject-matter of particular claims.

What I claim as my invention is—

1. In a machine for coating wafer-sheets, a sheet-plate having means for flattening and holding the sheet flat, and means for coating the sheet while thus held flat on the plate.

2. In a machine for coating wafer-sheets, a vertically-reciprocating sheet-plate, means for flattening and holding the sheet flat thereon, and means for coating the sheet while thus held flat on the plate.

3. In a machine for coating wafer-sheets, a movable sheet-plate, means for flattening the wafer-sheet on the plate, means for moving the plate to a coating mechanism, and said mechanism for coating the sheet.

4. In a machine for coating wafer-sheets, a movable sheet-plate, means for flattening the wafer-sheet thereon, a stencil-plate, a coating-receptacle adapted to be moved over the stencil-plate, means for moving the sheet-plate beneath the stencil-plate, means for reciprocating it against the stencil-plate and for lowering the plate and moving it away from the stencil-plate.

5. In a machine for coating wafer-sheets, a table, a plurality of sheet-plates thereon, means for rotating the table a partial rotation and stopping, means for reciprocating the table at the stopping-points, and a coating mechanism adapted to operate to coat a sheet upon a sheet-plate at one of the stopping-points.

6. In a machine for coating wafer-sheets, a table, a plurality of sheet-plates thereon, means for rotating the table successively partial rotations and stopping the same after each movement, means for reciprocating the table at the stopping-points, mechanism for coating the sheet at one stopping-point, and a presser-plate at another stopping-point for the purpose described.

7. In a machine for making wafer-sheet sandwiches, a table, a plurality of sheet-plates thereon, means for rotating the table successively partial rotations and stopping the same after each movement, means for reciprocating the table at the stopping-points, mechanism for coating the sheet at one stopping-point, a presser-plate at another stopping-point, said table stopping at a point intermediate the coating and pressing.

8. In a machine for coating wafer-sheets, the combination of a movable sheet-plate, the

plate O , means for moving said plate upon the wafer on the sheet-plate to flatten the same, and means for clamping the edges of the wafer-sheet while thus flattened.

9. The combination of the sheet-plate, the geared shafts along the edges of the sheet-plate, the arms p secured thereto, the clamping-flanges p' on the ends of the arms, and means for rocking the shafts to cause the clamping-flanges to engage over and withdraw from the edges of the sheet-plate, for the purpose described.

10. The combination of a traveling and reciprocating sheet-plate, the presser-plate O for flattening the sheet at the receiving-point, clamps for the edges of the sheet, and means for applying the clamps upon the downward reciprocation of the sheet-plate, substantially as described.

11. The combination of the reciprocating hopper, the stencil-frame beside the same, a series of wires or bars stretched across the opening in the stencil-frame, a sheet-plate, means for moving the sheet-plate up to the under side of the stencil-frame and for reciprocating the hopper over the frame.

12. The combination of the table, the sheet-plates thereon, means for moving and reciprocating the plates, the presser-plate above the table, and means for adjusting the plate to and from the table.

13. In a wafer-coating machine, the combination of a support for a wafer-sheet, means for flattening and holding the sheet flat thereon.

14. In a wafer-coating machine, mechanism for flattening a wafer-sheet and holding it flat, and coöperating automatic mechanism for coating the sheet while thus held.

15. In a wafer-coating machine, a stencil-plate having a series of cross-bars such as fine wires extending across the stencil openly, and a coating-hopper adapted to reciprocate across the stencil-plate.

16. In a wafer-coating machine, a coating mechanism for applying a layer of plastic material to a wafer on the wafer-holder, a presser, and an intermittently-traveling wafer-holder, said wafer-holder stopping at the coating mechanism at the pressing-point and at a point intermediate the coating and pressing points.

17. In a machine for making wafer-sandwiches the combination of an intermittently-traveling holder, mechanism for applying a layer of plastic material to a wafer-sheet on the holder, and a pressing mechanism, the coating and pressing mechanism being supported, and the wafer-holder stopping at the coating and pressing means, and at a point between the two.

18. In a machine for making wafer-sandwiches, the combination of coating mechanism adapted to apply a layer of plastic mate-

rial to a wafer-sheet on the sheet-plate, a presser, the sheet-plate, and means for moving said plate successively to the coating mechanism and presser.

5 19. In a machine for making wafer-sandwiches, the combination of separate coating mechanism and presser, a sheet-plate adapted to move successively to the coating mechan-

ism and presser, and means for holding a wafer-sheet flat on the plate while being coated.

In testimony whereof I affix my signature in presence of two witnesses.

ALEXANDER W. COPLAND.
